UNITED STATES PATENT OFFICE.

EDWIN R. CRAMER, OF NEWARK, AND OSCAR H. CRAMER, OF EDGEWATER, NEW JERSEY.

OIL PROJECTILE.

1,416,615.

Specification of Letters Patent. Patented May 16, 1922.

Application filed March 23, 1921. Serial No. 454,666.

To all whom it may concern:

Be it known that we, EDWIN R. CRAMER and OSCAR H. CRAMER, both citizens of the United States, and residents, respectively, of 5 Newark, in the county of Essex and State of New Jersey, and Edgewater, in the county of Bergen and State of New Jersey, have invented a new and Improved Oil Projectile, of which the following is a full, clear, and 10 exact description.

This invention relates to means for calming the sea by oil and has particular relation to an oil projectile.

It has been the common practice heretofore in event of the wrecking or disabling of a vessel to calm the sea adjacent thereto by dumping therein quantities of oil which forms a film to prevent breakers during the transfer of passengers to a rescue ship. Under this practice quantities of oil have been carried by each ship for this purpose but many disadvantages have been apparent due to the fact that the sea oftentimes washes the oil film away before the transfer of passengers can be completely effected. 25

It is therefore the principal object of the present invention to provide a projectile adapted to contain a quantity of oil which can be fired from the usual mortar used 30 for the purpose of projecting life lines whereby the oil contained therein may be released an appropriate distance from the vessel on the windward side.

A further object in view resides in the provision of a projectile of this character 35 which includes a receptacle and a nose constituting a cover for the open end of the receptacle and means for retaining said nose over the open end of the receptacle, which 40 means is operable when the energy of the projectile is spent to release the receptacle from the nose.

A further object in view is to provide a projectile of the character described which 45 is comparatively simple in its construction, inexpensive to produce and which is thoroughly reliable and highly efficient in its purpose.

With these and other objects in view, the 50 invention resides in the novel construction, combination and arrangement of parts set forth in the following specification, pointed out in the appended claims and illustrated in the accompanying drawings, in which—

55 Figure 1 is a longitudinal sectional view

through a projectile constructed in accordance with the invention and illustrating the normal arrangement of parts.

Figure 2 is a similar view illustrating the arrangement of parts when the energy of 60 the projectile has been spent.

Figure 3 is a horizontal sectional view taken approximately on the line 3—3 of Figure 1.

Figure 4 is a horizontal sectional view 65 taken approximately on the line 4—4 of Figure 1.

Figure 5 is a perspective view illustrating the position of the projectile when the energy for projecting the same has been spent. 70

Figure 6 is a detail perspective view of the actuating bolt used in connection therewith.

Referring to the drawings by characters of reference, the projectile includes a container 10 and a nose 11. The container 10 comprises a cylindrical shell 12 closed at its lower end by a head 13 provided with an enlarged annular flange 14. As illustrated the head 13 is provided with an annular 75 groove 15 into which a rib 16 is pressed or clinched, it being understood however, that any desired means of fastening the shell to the head may be employed in lieu of that illustrated. The nose 11 at its inner end is 80 substantially the same diameter as the greatest diameter of the flange 14 and tapers toward its outer end to a central point to reduce the head resistance of the projectile to a minimum. An annular reduced boss 17 85 projects inwardly from the inner end of the nose 11, the external diameter thereof being of substantially the same size as the internal diameter of the shell 12 whereby the same may be telescopically received thereby. The 90 boss 17 is provided with a plurality of radially disposed openings 18 which are inclined inwardly or downwardly. The shell 12 is provided adjacent its open end with a plurality of semi-spherical sockets 19 in its inner periphery which are designed to align or register with the outer ends of the openings 18 when the boss is telescopically positioned in the shell. In order to provide means for

detachably associating the nose 11 with the 105 container, a plurality of retaining pins 20 are employed and arranged in the openings 18. The outer extremities 21 of the retaining pins 20 are preferably of semi-spherical formation whereby upon radial projection 110

thereof said extremities will be received by the sockets 19. The nose 11 is provided with a central bore 22 extending into the same from the inner end thereof and communicating with the interior of the boss 17. An actuating bolt 23 having a conical head 24 and a circular shank 25 provided with a conical extremity 26 is provided and said shank 25 is arranged for sliding movement in the bore 22. The sides of the conical head are provided with flattened wedge faces 27 which are designed to engage and co-act with the inner ends of the retaining pins 20 for the purpose of effecting the radial projection of the semi-spherical ends from the boss upon outward sliding movement of the actuating bolt 23. A pair of triggers 28 are pivoted within the slots 29 of the nose at diametrically opposite sides of the bore 22 as at 30 and said triggers are provided with retaining fingers 31 and release fingers 32. The free outer ends of the triggers are provided with semi-cylindrical wings 33 which are preferably formed integral therewith. The retaining fingers 31 are designed to co-act with the arcuate notches 34 formed in the shank 25 of the actuating bolt at diametrically opposite sides thereof, for the purpose of shifting said bolt outwardly and retaining the same in its shifted position. The wings 33 are designed to embrace and house the container when the bolt is shifted outwardly, the free ends of said wings being positioned adjacent to the annular flange 14. The wings 33 when in this position are of substantially the same diameter as the major diameter of the annular flange and the nose, the inner periphery of said wings being slightly spaced from the outer periphery of the shell 12. The flange 14 is provided with a plurality of flared ports 34 which extend therethrough and communicate with the space between the wings and the shell 12, for a purpose to be hereafter set forth: The head 13 is provided with a central filling opening 35 which permits the oil 36 to be introduced to the shell after the nose has been attached thereto by inverting the projectile. A plug 37 is then inserted for closing said filling opening. The oil used is preferably of a thick consistency and the small quantity which might leak through the bore 22 will serve as a means for lubricating the triggers and the retaining pins. The head 13 is preferably of a sufficient weight to over-balance the nose end of the projectile whereby when the energy for projecting the projectile is spent, the projectile will drop as illustrated in Figure 5 of the drawings.

In use and operation of the projectile, the same is used in connection with the ordinary form of life line mortar now installed on each vessel by placing the charge 65 in the mortar and then inserting the projec-

tile in the muzzle, with the head 13 adjacent to the charge. The mortar will be aimed and fired in the direction desired and when the force of the projectile has been spent, the inner end will cause the same to fall 70 with the nose up. The descent of the projectile in this manner will cause currents of air to enter the space between the wings 33 and the shell 12 through the ports 34 thereby effecting an initial opening of the wings. 75 The air will further act on the wings to throw the same to a horizontal position as illustrated in Figure 5 where the triggers 28 will contact with the upper walls of the slots 29 to stop the same. This movement of 80 the wings will swing the triggers to the position illustrated in Figure 2 thereby releasing the retaining fingers 31 from the notches 34 in the actuating bolt 23, at the same time the releasing fingers 32 will engage and co-act with the conical extremity 26 of the bolt to shift the same downwardly or inwardly. As the bolt moves inwardly, the wedge faces 27 will permit of a radial contraction of the retaining pins 18 thereby 85 disengaging the semi-spherical outer ends 21 thereof from the sockets 19 and permitting of the separation of the container from the nose to distribute the oil contained therein over the surface of the sea. By the use of 90 this projectile a film of oil may be disposed over the surface of the sea to the windward of a disabled vessel so that the film will move toward the vessel and permit of the transfer and rescue of passengers. The 95 projectile will also be especially useful to effect the arranging of small rescue boats from the shore by firing projectiles a sufficient distance to spread a film over the breakers. 100

While there has been illustrated and described a preferred embodiment of the invention, no limitation is necessarily made to the precise structural details, as it is to be understood that variations and modifications which properly fall within the scope of the appended claims may be resorted to when found expedient.

We claim:

1. A projectile of the character described including a container shell having a closed weighted end and an open end, a nose constituting a closure for said open end, interengageable means provided respectively on the shell and closure for normally retaining said closure in closed relation with respect to the open end, said means being disengageable when the force of the projectile is spent by the vertical descent of the projectile with its weighted end foremost, whereby to effect separation of the container from the closure. 115

2. A projectile including a container shell having a closed weighted end and an open end, a nose constituting a closure adapted to 120

125

130

135

fit within said open end, means on the shell and means on the closure adapted for inter-engagement to retain the closure in closed relation with respect to the open end of the shell, the means on the nose being movable after the force of the projectile is spent by the vertical descent of the same with the weighted end foremost to effect disengagement of the same from the means on the shell whereby to permit of separation thereof and the discharge of the contents of the shell.

3. An oil projectile comprising a hollow cylindrical receptacle having a closed weighted end, a nose constituting a closure for the open end thereof, means carried by the nose for retaining the same in closed relation to the open end and a second means carried by the nose adapted to co-act with the first means when the energy of the projectile is spent to release said retaining means for effecting separation of the nose from the receptacle and the discharge of its contents.

25 4. An oil projectile comprising a cylindrical shell having a closed weighted end and an open end, a nose constituting a closure therefor, a plurality of sockets in the shell adjacent its open end, a plurality 30 of radially projectible retaining pins carried by the nose and adapted to be received by the sockets for retaining the nose in asso-

ciated relation with the shell, a longitudinally slideable bolt mounted in the nose and adapted to co-act with the retaining pins 35 for effecting radial projection thereof, and pivoted wings carried by the nose and adapted to co-act with the bolt for shifting and retaining the same to a position to project the retaining pins when said wings are 40 arranged in closed position, and means carried by said wings and operable to effect a shifting of the bolt to permit of radial contraction of the retaining pins when the wings are open.

5. An oil projectile including a receptacle having a closed weighted end and an open end, a nose constituting a closure for said open end and means for retaining said nose in closed relation to said open end comprising 50 sockets formed in the receptacle and pins carried by the nose and projectible into said sockets, and means for normally retaining said pins projected during the flight of the projectile, said means being 55 operable when the energy of the projectile is spent to permit of the radial contraction of the pins whereby separation of the nose from the receptacle will be effected to discharge the contents thereof, as and for the 60 purpose specified.

EDWIN R. CRAMER.
OSCAR H. CRAMER.
